UNITED STATES PATENT OFFICE.

WILLIAM E. GWYER, OF NEW YORK, N. Y.

GOVERNOR FOR VULCANIZING APPARATUS.

SPECIFICATION forming part of Letters Patent No. 239,490, dated March 29, 1881.

Application filed February 24, 1881. (No model.)

To all whom it may concern:

Be it known that I, WILLIAM E. GWYER, of the city, county, and State of New York, have invented a new and useful Improvement in 5 Governors for Vulcanizing Apparatus, of which the following is a specification.

My improvements relate to governors for regulating the flow of gas to the steam-generators of vulcanizing apparatus, by which the 10 temperature in the vulcanizing-chamber is maintained at a uniform point.

The object of this invention is to utilize an ordinary pressure-diaphragm for that purpose, and also to allow escape from the steam-space 15 or steam-generator of expanded air, which, when allowed to remain, interferes with the proper indication of the pressure.

In the accompanying drawings, forming part 20 of this specification, Figure 1 is a sectional elevation of the governor. Fig. 2 is a face view of the same, and Fig. 3 is a cross-section of the gas-cock.

Similar letters of reference indicate corresponding parts.

25 A is a hollow plug, adapted for connection, by a pipe or otherwise, with the shell of the steam-generator of the vulcanizer, (shown by dotted lines,) which is of usual construction. The upper end of the tube is formed or fitted 30 with chambered enlargement *a*, of circular form, in which a circular flexible diaphragm, *b*, of ordinary character, is held by the face-plate *c* that covers the chamber.

g is a lever pivoted on the face-plate *c* and 35 fitted with a screw, *h*, that extends through a central aperture in plate *c*, and bears upon the diaphragm *b*.

i is the gas-cock fitted in the gas-supply pipe *k*, between the source of supply and the burners, (not shown,) and having its stem *d* connected with the lever *g*. The valve is 40 constructed to cut off and to open the gas-pipe by a limited extent of movement, for which purpose the valve-case *l* separates the gas-pipe, 45 and the separated ends connect with passages *m m* that extend to the face of the valve-seat. The valve *n* is a disk on the end of stem *d*, which carries a spiral spring, *e*, tending to retain the valve off from its seat, and thus allow 50 communication between the passages *m*.

The passage in plug A communicates with

the space at the back of diaphragm *b*, so that the steam has access thereto, and it will be seen that the tendency of pressure on the diaphragm is to move the lever *g* outward, thus 55 moving stem *d* in the direction to close the valve to its seat.

At one side of plug A, and communicating with the passage therein, the relief-cock *B* is placed. This cock consists of a chambered 60 case, *o*, in which is fitted a disk-valve, *p*, having a stem, *q*, that extends through a central aperture in the cap *o'* of the valve-case. The stem *q* is grooved lengthwise, as shown at *q'*, to allow escape of air from the case. The valve *p* 65 has suitable packing on its face to close tightly against the under side of cap *o*, and the valve is placed to fall and open the passage *q'* by gravity.

In operation, the burners being lighted under 70 the generator, the air therein, or in the steam-space of the vulcanizer, is first heated and, by its expansion, passes through the cock *B*, until the steam-pressure is sufficient to close the valve *p*, by which time the air will have nearly 75 all escaped. As the pressure of steam increases the lever *g* is moved, by the action of diaphragm *b*, until the pressure reaches the point at which the apparatus is set, when the valve *n* will have checked the flow of gas to the minimum 80 amount. The heat of the generator being thus reduced, the steam pressure-falls, diaphragm *b* reacts, and the gas-cock opens. The diaphragm *b* will act correctly according to steam-pressure, on account of the absence of expanded 85 air, which, in the comparatively small steam-space of a vulcanizer, is an important factor for pressure. The correct ratio between pressure and heat can therefore be obtained.

There may be a loose connection between 90 lever *g* and stem *d*, so that the lever may move a certain distance outward before producing any effect on the stem.

An ordinary cock, *r*, is fitted in the coupling-thimble of cock *B*, so that the passage can be 95 closed by hand, if desired. This may be done when steam is raised, in order to prevent wear of the relief-valve and leakage of steam.

Having thus fully described my invention, I claim as new and desire to secure by Letters 100 Patent—

1. In governors for vulcanizing apparatus,

the flexible pressure-diaphragm *b*, lever *g*, and gas-cock having its stem connected with the lever, combined together and with hollow plug *A*, adapted for connection with the shell of a vulcanizer, substantially as shown and described.

2. The combination, with governors for vulcanizers actuated by steam-pressure, of an au-

tomatic relief cock or valve for escape of air from the steam-generator, substantially as shown and described.

WILLIAM E. GWYER.
